AUTOMOBILE LAMP CLUSTER

Harley J. Earl, Grosse Pointe Farms, and Ned F. Nickles,
Detroit, Mich., assignors to General Motors Corporation,
Detroit, Mich., a corporation of Delaware

Application September 9, 1954, Serial No. 32,204

Term of patent 7 years

(Cl. D48—32)

Fig. 1

Fig. 2

Fig. 3

To all whom it may concern:

Be it known that we, Harley J. Earl, a citizen of the United States of America and a resident of Grosse Pointe Farms, Michigan, and Ned F. Nickles, a citizen of the United States of America and a resident of Detroit, Michigan, have invented a new, original, and ornamental Design for an Automobile Lamp Cluster, of which the following is a specification, reference being made to the accompanying drawing, forming a part thereof.

In the drawing:

Fig. 1 is a side elevational view of an automobile lamp cluster showing our new design;

Fig. 2 is a rear view thereof looking from the right of Fig. 1; and

Fig. 3 is a top plan view thereof.

We claim:

The ornamental design for an automobile lamp cluster, substantially as shown.
